E. TYDEN,
PUMP JACK,
APPLICATION FILED MAY 13, 1920.

Patented Feb. 1, 1921.

UNITED STATES PATENT OFFICE.

EMIL TYDEN, OF HASTINGS, MICHIGAN.

PUMP-JACK.

1,367,217.

Specification of Letters Patent.

Patented Feb. 1, 1921.

Application filed May 13, 1920. Serial No. 381,033.

To all whom it may concern:

Be it known that I, EMIL TYDEN, a citizen of the United States, residing at Hastings, in the county of Barry and the State of Michigan, have invented certain new and useful Improvements in Pump-Jacks, of which the following is a specification, reference being had to the accompanying drawings, forming a part thereof.

10 The purpose of this invention is to provide an improved structure of the nature of a pump jack, the specific purposes being to make such jack in such form that the working parts may be inclosed in a casing forming a grease receptacle, so that lubrication may be provided for without waste of grease or frequency of attention. A further purpose is to provide a very compact and economical construction. The invention consists in the elements and features of construction shown and described, as indicated in the claims.

In the drawings:

Figure 1 is a side elevation showing a pump adapted for connection for driving it by a wind mill, and also for hand operation by a pump lever, and equipped with a jack embodying this invention.

Fig. 2 is a front elevation of the same.

30 Fig. 3 is a partly sectional elevation from the opposite side from that shown in Fig. 1, the cover member of the casing being removed and the pitman-carried hood being shown in section at the plane of junction of the cover and casing.

35 Fig. 4 is a section at the line, 4—4, on Fig. 3.

Fig. 5 is a section at the line, 5—5, on Fig. 3.

40 Fig. 6 is a detail side elevation of a portion of the operating chain showing a special form of link having guard shoes for preventing the in-buckling of the chain.

In the construction shown in the drawings, 1 represents the pump standard, 2, the plunger rod, 3, the pump-operating handle lever. 4, 4, are pitman links connecting the hand lever with the pump plunger rod, 2. It will be understood, of course, that these 45 details of construction of the pump are not any part of the present invention, the pump being of necessity shown to illustrate the mode of use and serviceability of the pump jack. The pump jack comprises a casing 50 consisting of two members, 5 and 6, secured together at a grease-tight joint by means of

their respective flanges, 5^a and 6^a, and formed so that when thus secured together there is produced a slot, 5^b, at the upper side for the emergence of the pitman link of the 60 jack, as hereinafter more particularly described. Mounted within the casing upon stud axles projecting inward from the lateral wall of the casing member, 5, are sprocket wheels, 7 and 8, about which the 65 endless chain, 9, travels. The upper sprocket wheel, 8, has the stud, 10, upon which it is journaled formed unitarily with the casing member, 5. The stud axle for the lower sprocket wheel, 9, is preferably an independent 70 machined stud which is formed with a shoulder, 11^a, whose reduced end, 11^b, is driven back to the shoulder tight into a boss, 5^c, with which the casing member, 5, is provided, the stud axle being permanently secured in the casing by being upset at the outer end as shown at 11^c. 12 is the jack pitman which is pivotally connected at the lower end to one of the links of the chain, 9, as shown by the pivot stud 1^a. At its upper 80 end it is pivotally connected by means of a clamp or clasp, 14, to the pump handle, 3, at a position immediately in the rear of the hand-hold of said handle lever. The endless chain-carrying sprocket wheels are driven 85 by a pinion, 16^a, meshing with a gear, 15, formed integrally with the lower sprocket wheel, 9. Said pinion, 16^a, is preferably formed by cutting its teeth on the inner end of the shaft, 16, which is journaled in an 90 elongated exteriorly-protruding boss, 5^e, of the case member, 5, the formation of the pinion in the manner described on the inner side of said shaft by in-cutting the teeth, 95 permitting the introduction of the integral shaft and pinion through the shaft bearing from the outer side; and the shaft is retained in its bearing by a key pin, 24, engaging a circumferential groove, 16^c, formed in the shaft back of the pinion end. Power is 100 communicated to the shaft, 16, by a drive pulley, 18, which is pressed from sheet metal in cup or dish form, the web 18^a, being secured to the protruding end of the shaft, 16. Preferably said shaft, 16, is terminated with 105 the radially-extended flange, 16^b, and the web, 18^a, of the pulley, 18, is further struck out or recessed at 18^b to accommodate the flange, 16^b. A grease drip-return sleeve, 19, most conveniently formed in cup form,— 110 that is, with a bottom or end web, 19^a, has said web interposed between the end of the

shaft or its flange, 16^b, and the web 18^a of the pulley, 18, so as to be secured to the shaft together with the pulley; and a reinforcing disk, 20, is provided, applied outside of the said web, 18^a, of the pulley, said reinforcing disk being similarly struck out or recessed at 20^a, so that the three parts, the grease-drip-return member, 19, the recessed portion, 18^b, of the web, 18^a, of the pulley, and the recessed portion, 20^a, of the reinforcing disk, 20, are nested together in their application to the flange, 16^b, which terminates the shaft, 16, and for securement of all said parts together to the shaft by means of rivets, 21, which effect said securement to the flange of the pulley. This flange is provided, in lieu of terminating the shaft without enlargement, especially for the advantage which is thus afforded of securing the parts mentioned to the shaft by riveting, whereas, otherwise it would be necessary to use screws engaging tapped holes in the end of the shaft, which is a less secure and more expensive method.

25 It will be observed that when the device as thus far described is in operation, the casing may be filled with grease up to the journal bearing of the combined sprocket wheel and gear, 9, 15, and that the gear-and-sprocket wheel and the chain dipping in the grease will carry it to all the parts requiring to be lubricated, including the intermeshing gear, 15, and pinion, 16^a, the chain at all its links, the pivotal connection of the pitman, 12, to the chain, the engagement of the chain with both the sprocket wheels and the journal bearing of the upper sprocket wheel.

30 In order to prevent leakage outside of the casing and loss of grease which might work out through the journal bearing of the shaft, 16, in the boss, 5^c, a grease-return sleeve, 19, is provided as above mentioned, and to take the drip for delivery from this sleeve which 35 at its inner end is outwardly flanged, as seen at 19^b, the casing member, 5, is expanded at the outer side toward the pulley, as seen at 5^a, forming a chamber or cavity, 5^f, which extends around the boss, 5^c, which supports 40 the stud axle, 11, of the sprocket and gear wheel, 9-15, and also around the initial or base portion of the boss, 5^c, in which the shaft, 16, is journaled; and said casing is further expanded to form an annular flange, 5^m, encompassing the said bearing, 5^c, and spaced off therefrom to form the annular opening through which the grease drip sleeve, 19, is protruded. This causes the inner end of said drip sleeve to extend within 45 the cavity, 5^f, and deliver the grease which may be gathered, back into said cavity; and this cavity is connected at its lower side by the aperture, 5^g, with the main cavity of the casing. But in fact the grease originally supplied to the casing occupies the

50 cavity, 5^f, to the same level to which it stands in the main cavity of the casing. It will be observed that the only opening or joint through which grease could escape from the casing is the journal bearing of the shaft, 16; so that the above described provision for returning any grease drip which may work out through this bearing insures the retention of all the grease in the casing, avoiding entirely waste of grease while insuring complete lubrication of all the parts.

55 In view of the oscillation of the pitman, 12, which is a necessary incident of its lateral swing as it passes around the sprocket wheels, and also of the vibration of the pump handle at the upper end, the slot, 5^b, at the upper side of the casing is required; and it becomes necessary to provide against water or dirt entering the casing through this slot. For this purpose there is provided the hood, 25, which tapers from its upper end where it is closely fitted around the pitman, to its lower end where it extends over the entire length and width of the slot, 5^b. This hood is supported by being pivoted intermediate the edges of its expanded lower end to flanges, 5^x and 6^x, with which the casing members, 5 and 6, respectively, are provided, around the slot, 5^b, a pivot bolt, 26, supporting said hood and permitting it to oscillate with the pitman, its ends extending down outside the flanges, 5^x, 6^x, insuring complete closure of the slot and the diversion outside the casing of any water which flows down the hood.

60 Upon consideration of the operation of the chain drive of the pitman, 12, operating the pump, it will be seen that there will be a tendency to thrust inward,—that is, toward the plane containing the axes of the two sprocket wheels,—the link of the chain to which the pitman is pivoted as the pivot is being carried across the interval between the two sprocket wheels in either course of the chain; and it will be seen that this inward thrust has a tendency to cause the chain to become locked on one sprocket wheel or the other,—that is, the tendency would be to prevent the link from clearing the last engaged sprocket of the sprocket wheel from which the chain was moving at the time of such inward thrust. To prevent such inward thrust and the resultant tendency to lock the chain, there is provided a shoe extension, 27, of the same link to which the pitman is pivoted, said shoe extending in both directions from its pivot,—up and down, as seen in Figs. 3 and 6,—to lap onto the adjacent links of the chain at both sides, on the outer side thereof,—that is, on the side remote from the sprocket wheel; thus insuring the chain remaining practically straight during this part of its course.

65 In order to permit adjustment to vary the length of the pump stroke by shifting

the engagement of the pitman, 12, along the pump handle lever, 3, the jack casing is mounted on the pump valve, 1, by means of two clamps, 22 and 23, the former a two-part 5 clamp located at the lower end of the pump valve and of the casing and secured to the casing by one of the clamping bolts, 22^a, and the other a one-part clamp folded to form an eye, 23^a, which 10 encircles the pump barrel and is clamped thereto by the bolt, 23^b; and the two arms, 23^c, extending parallel for embracing the jack casing members, 5 and 6, between them, are secured to the casing by a bolt, 23^c. 15 For the adjustment mentioned said parallel arms have each a series of bolt holes, 23^c, and the adjustment is made by swinging the casing on the bolt, 22^a, as a pivot, to bring any selected hole of the series into 20 registration with the bolt holes in the jack casing at which the securing bolt, 23^d, is inserted. The clasp, 14, by which the pitman, 12, is secured to the pump handle lever, 3, is slideable along the pump handle and it 25 may be clamped in position corresponding to the adjustment of the casing as indicated.

I claim:—

1. A pump jack comprising a casing adapted to contain grease, which is closed 30 except as to driving shaft and pump rod emergences; an endless chain, and sprocket wheels within the casing about which the chain travels; means for mounting the casing upon the standard or main barrel of the 35 pump to be served with the path of the endless chain between the sprocket wheels approximately vertical; one of the sprocket wheels having a gear rigid with it; a driving shaft journaled in the side wall of the 40 casing, and a pinion on the inner end of the shaft within the casing meshing with said gear on the sprocket wheel.

2. In the construction defined in claim 1 foregoing, the casing being formed with an 45 exteriorly-projecting, relatively long boss, in which the shaft journal bearing is formed extending therethrough, and a drive pulley in the form of a cap or cup having its web or bottom secured to the outer end of the 50 shaft and its wall or flange constituting the belt-carrying face of the pulley encompassing the protruding shaft bearing boss.

3. In the construction defined in claim 1 foregoing, the casing having an exteriorly-projecting boss in which the shaft journal bearing is formed extending therethrough, said shaft having at its outer end a radially-projecting flange for stopping the shaft upon the outer end of said boss, and a drive 60 pulley in cup or cap form having its web or bottom riveted to the said flange at the outer side thereof, the securing rivets taking through the overhanging flange beyond the diameter of the shaft proper.

4. In the construction defined in claim 1

foregoing, the casing having an exteriorly-projecting boss affording journal bearing for the shaft which extends therethrough, the casing having also an annular flange encompassing said journal bearing boss, 70 spaced away therefrom and recessed back therefrom at the lower side, and a sleeve-like member secured on the protruding end of the shaft extending inward toward the casing and encompassing said journal boss 75 and entering within the annular boss for delivering oil drippings into the recess of the latter.

5. A pump jack comprising in combination with a casing and means for mounting 80 it upon the standard or barrel of the pump to be served, sprocket wheels journaled in said casing and an endless chain encompassing and traveling about the same; a pitman pivotally connected with a link of said chain 85 and extending out of the casing for operative connection with the pump plunger rod, the casing having at its upper end a slot in which the pitman may oscillate as it is carried at its lower end around the sprocket 90 wheels, the water-shedding hood encompassing said pitman and fitting it closely at its upper end, and tapered thence downward for overhanging and extending laterally with respect to the swing of the pitman 95 beyond the ends of the slot and means engaging it at its lower end with the upper end of the casing for sliding at that end back and forth along the slot as the pitman oscillates.

6. In a pump jack, in combination with a casing, two sprocket wheels therein and an endless chain encompassing and traveling about said sprocket wheels; a pitman pivotally connected at its lower end to a link of 100 the chain extending out through the upper end of the casing, the latter being slotted for emergence of the pitman and to accommodate its oscillation as it is carried by the chain around the sprocket wheel at its lower 105 end; a water-shedding hood encompassing the pitman and at its upper end fitting said pitman closely, said hood being pivoted at its lower end to the casing and extended in the direction of oscillation of the pitman to 110 overhang the slot in the casing through which the pitman emerges and in which it oscillates, the casing having flanges bounding said slot, and the hood at its lower end extended to embrace said flanges through 115 the entire range of oscillation of the hood about its pivotal connection with the casing.

7. In a pump jack in combination with a casing, a pair of sprocket wheels therein; an endless chain encompassing and traveling 120 about the sprocket wheels; a pitman for engagement with the pump plunger rod operating handle at its upper end, having its lower end pivotally connected with a link 125 of the chain, and a shoe carried by the same 130

link and extending both ways from its pivot to face or overhang the adjacent links at both sides of the link by which it is carried, and adapted to bear against the outer side 5 of said adjacent links at straightened-out position of the chain near its passage between the sprocket wheels.

8. In combination with a pump, a jack for operating it having its casing pivotally 10 mounted on the pump barrel at the lower end thereof, and means for securing it at a

variety of angularly adjusted positions about said pivot, said jack comprising a pitman for operating the pump handle lever, and means adjustable along said pump 15 handle lever for connecting the pitman to said lever.

In testimony whereof, I have hereunto set my hand at Chicago, Illinois, this 11th day of May, 1920.

EMIL TYDEN.
